UNITED STATES PATENT OFFICE.

JOHN SCHOFIELD, OF HOLYOKE, MASSACHUSETTS, ASSIGNOR TO THE CHADWICK PLUSH COMPANY, OF SAME PLACE.

DESIGN FOR A PLUSH FABRIC.

SPECIFICATION forming part of Design No. 22,233, dated February 21, 1893.

Application filed January 13, 1893. Serial No. 458,284. Term of patent 3½ years.

To all whom it may concern:

Be it known that I, JOHN SCHOFIELD, of Holyoke, in the county of Hampden and State of Massachusetts, have invented a new Design for Plush Fabrics, of which the following is a specification.

The leading feature of this design consists in the representation of flowers *a*. with radial leaves; stems *b*. and intersecting leaves *c*. *d*. and buds upon the surface of a plush fabric as represented in the accompanying draw-

ing. Part of a border is represented at *e*. as inclosing the design, but such border does not necessarily form a part of the design.

I claim—

The design for a plush fabric as herein described and shown.

Signed by me this 5th day of January, 1893.
JOHN SCHOFIELD.
